[57] CLAIM

The ornamental design for a movable lettering advertising display, substantially as shown and described.

DESCRIPTION

FIG. 1 is a front elevational view of a movable lettering advertising display showing my new design;

FIG. 2 is a top plan view thereof;

FIG. 3 is a right side elevational view, the left side being a mirror image thereof; and

FIG. 4 is a sectional view thereof taken along line 4—4 of FIG. 1.

The broken line disclosure of the letters in FIG. 1 is for illustrative purposes only and forms no part of the claimed design.
